UNITED STATES PATENT OFFICE

FRANK J. GORIUP, OF PITTSBURGH, PENNSYLVANIA, ASSIGNOR TO WOLVERINE SUPPLY & MANUFACTURING COMPANY, OF PITTSBURGH, PENNSYLVANIA, A CORPORATION OF PENNSYLVANIA

TOY

Application filed May 20, 1929. Serial No. 364,357.

More particularly my invention comprises a toy "water-mill" wherein the mill-wheel is operated by means of sand falling into the wheel buckets.

5 The hopper for the sand is contained in a housing representing a mill building, and the discharge of the sand onto the wheel is controlled by a suitable gate.

Associated with the mill-wheel and caused 10 to be moved thereby is a figure or figures, the same being preferably caused to move on a platform in front of the mill.

Other novel features of construction, and 15 also of arrangement of parts, will appear from the drawings and from the following description.

In the accompanying drawings, Fig. 1 is a front elevation of the toy, portions of the mill-wheel being broken away.

20 Fig. 2 is a plan view partially in horizontal section along the line 2—2 in Fig. 1.

Fig. 3 is a vertical section along the line 3—3 in Fig. 1, the piers of the mill being omitted for the sake of clearness.

25 Fig. 4 is a detail in section of the eccentric and associated parts.

Referring to the drawings, 1 is a metal box or housing, provided with a removable cover or lid 2 which may be hinged or otherwise 30 connected to the box. The housing 1 and the lid 2 are preferably so shaped, colored and marked to represent an antique mill building and its peaked roof.

The housing is elevated on piers or legs 35 3 which are connected and braced intermediate of their height by the horizontal struts 4.

A horizontally disposed axle 5 is mounted 40 in bearing holes in the front and rear struts 4, and protrudes at the front center of the toy.

Rotatably mounted on the front end of the axle 5 is the mill wheel which comprises two circular disks 6 and 7 of sheet metal which are spaced apart by the annulus 8 of sheet 45 metal which is of less diameter than the disks 6 and 7.

The inner disk 7 is cut inwardly from its 50 perimetral edge on lines tangentially disposed to a circle described from the axis of the disk and tongues or portions 9 of the

metal are bent over to abut against the inner surface of the outer disk 6, the ends of the tongues being squared to fit flat against the latter disks. The tongues 9 are provided with spurs 10 which extend through holes 55 punched in disk 6 and are clinched against the outer surface of disk 6, thus holding the parts of the wheel in assemblage. The bent tongues 9 serve to hold the annulus 8 in place in the wheel.

The tongues 9, the outer surface of the annulus 8 and the walls of the disks 6 and 7 60 form wheel buckets 11 which are arranged to cause the wheel to rotate clockwise in Fig. 6 when sand is dropped down into the buckets.

65 For the purpose of supplying sand to the buckets, the interior of the housing 1 is provided with a sand hopper formed by securing in the front right hand corner of the housing a triangular curved metal sheet 12.

The right end wall of the housing 1 is provided near its bottom with an opening 13 which communicates with the lower end of the hopper, and fixed to the outer face of the wall is an inclined chute 14 whose outer and lower end is disposed above the path of the buckets 11 at the right of the vertical axis 70 of the mill wheel.

The opening 13 may be elongated in an inclined plane parallel with that of the floor 80 of the chute.

75 15 is a gate formed of flat metal and pivoted to the housing 1 on a stand 16 so that the gate may be moved into position to close the opening 13 from without or to expose the opening and permit the sand to flow from the hopper into the chute.

The gate is provided with an angular portion or handle 17 which protrudes at the front of the housing 1 so that the gate may be 85 manually opened or closed at will. The stand 16 is provided with a stop 18 to limit the opening of the gate.

90 It is obvious that with a supply of sand in the hopper, if the gate be opened, the sand will flow out and down the chute and drop into the buckets, thus causing the wheel to rotate and continue its rotation until the gate is closed or the sand in the hopper is exhausted.

6 A curved guard 19 supported from one of the piers 3, incloses a portion of the perimeter of the wheel, in advance of the point where the sand is discharged into the buckets, to prevent the sand from dropping out of the buckets before the latter reach the bottom of the wheel.

10 Moving with the wheel is a perimetral flange eccentric 20. The same may have its web secured to the ends of the fingers 21 which are formed by cutting the metal of the disk 7 and striking out the cut strips so that they extend rearwardly and are disposed about and parallel with the axle 5.

15 The perimetral edge flange of the eccentric 20 is engaged by a slot in the bent end 22 of the lower and shorter arm of a bell-crank lever 23 which is pivotally mounted at its angle on a stand 24 extending up from the front strut 4.

20 The other and longer arm of the lever 23 extends up through a slot in a platform 25 extending from the front of the housing 1 and is pivotally connected to a representation of a figure 26 of a man, made to represent a miller in antique costume and preferably accompanied by a dog.

25 The contour of the perimetral flange of the eccentric 20 is such that the figure 26 is caused to periodically dart forwardly and be partially exposed beyond the end of the housing 1 and then quickly withdrawn, giving the appearance of momentarily peering beyond the end of the mill and dodging back again.

30 The platform acts to prevent the figure from rotating on the end of its actuating lever and to aid in maintaining the figure in its proper posture, the metal of the figure may be cut and bent to form a projection 27 on the rear side of the figure which by coming into contact with the upper end of the lever acts as a limiting stop.

35 It is evident that the toy is of simple and inexpensive construction and yet substantial and durable. It is attractive as an amusement toy.

40 What I desire to claim is:—

45 1. In a toy "water-mill," the combination of a wheel arranged to rotate on a horizontal axis and provided with buckets, a sand hopper located above the wheel, controlled means for gravity discharge of sand from the hopper into the buckets of the wheel whereby to rotate the wheel, a movably mounted mechanical figure, a bell-crank lever having its upper end pivotally connected to the figure, means whereby the rotation of the wheel causes a rocking of the bell-crank lever whereby to move the figure and a horizontal platform over which said figure trails in its movements whereby said figure is prevented from material tilting.

50 2. In a toy "water-mill," the combination of a wheel arranged to rotate on a horizontal axis and provided with buckets, a sand

55 hopper located above the wheel, controlled means for gravity discharge of sand from the hopper into the buckets of the wheel whereby to rotate the wheel, a movably mounted mechanical figure, an eccentric rotating with the wheel, a bell-crank lever rocked by said eccentric and having its upper end pivotally connected to the figure whereby to move the latter and a horizontal platform over which said figure trails in its movements whereby said figure is prevented from material tilting.

60 Signed at Pittsburgh, Pa., this 13th day of May, 1929.
